UNITED STATES PATENT OFFICE.

WILSON E. PORTER, OF NEW HAVEN, CONNECTICUT, ASSIGNOR TO NEW HAVEN CLOCK CO., OF NEW HAVEN, CONNECTICUT, A CORPORATION.

CHIME-CLOCK.

1,300,771.

Specification of Letters Patent. Patented Apr. 15, 1919.

Application filed October 17, 1917. Serial No. 197,150.

To all whom it may concern:

Be it known that I, WILSON E. PORTER, a citizen of the United States, residing at New Haven, in the county of New Haven and State of Connecticut, have invented a new and useful Improvement in Chime-Clocks; and I do hereby declare the following, when taken in connection with the accompanying drawings and the characters of reference marked thereon, to be a full, clear, and exact description of the same, and which said drawings constitute part of this application, and represent, in—

Figure 1 is a view in front elevation of a self-contained time, strike and chime clock-movement constructed in accordance with my invention, the dial-work of the time-mechanism and the rack-and-snail features of the strike-mechanism being omitted.

Fig. 2 a view of the movement in rear elevation.

Fig. 3 an edge view thereof.

Fig. 4 a detached perspective view of the count-wheel latch, lifting-lever, lifting-dog and stop-lever, in their related positions.

Fig. 5 a detached perspective view of the releasing-lever.

My invention relates to an improved chime clock, and is particularly adapted for incorporation in clock-movements of the marine type though not so limited, the object being to produce a reliable, relatively simple, self-contained chime clock-movement constructed with particular reference to compactness of form, and to the reduction of the number of parts to the minimum.

With these ends in view, my invention consists in a self-contained chime clock-movement comprising a time-train, a chime-train and a strike-train constructed arranged and connected so that the chime-mechanism is instantaneously released periodically by the time-mechanism without warning the former, whereby the use of a warning mechanism for the chime-train is dispensed with.

My invention further consists in a self-contained chime clock-movement having certain details of construction and combinations of parts, as will be hereinafter described and pointed out in the claims.

The prime characteristic of my improved self-contained clock-movement is the periodic instantaneous release of the chime-train by the time-mechanism without the

employment of the usual warning mechanism, whereby I simplify the clock-movement to that important extent, both as to operation and number of parts.

In carrying out my invention as herein shown, I employ a releasing-lever 2 which is located, together with the parts with which it co-acts, in front of the front movement-plate 3, which mounts the forwardly projecting stud 4 on which the said lever oscillates. At its lower end, the lever is formed with an arm 5 for the attachment of a helical operating spring 6 the upper end of which is fastened to an adjustable arm 7 held in place by a screw 8 entering the plate 3, the said spring being regulated in tension so as to "snap" the lever from right to left with the force required for the operation of the counter-weighted lifting-dog 9. A stop-pin 10 mounted in the plate 3, limits the throw of the lever 2 from right to left. The said lever has an operating-face 11 successively engaged by four quarter-hour-chime lifting-pins 12 mounted at equal distances apart in a disk 13 secured to the cannon-pinion 14 upon the center arbor 15 which is a member of the time-mechanism of the clock-movement. As the disk is turned clockwise by the time-train, the pins 12 successively engage with the face 11 and gradually swing the lever 2 from left to right against the tension of its spring 6. When, in this movement, any one of the pins 12 passes the point 16 at the lower end of the face 11, the lever 2 is snapped, so to speak, from right to left by the action of its spring 6 aforesaid for the operation of the dog 9 as will be more fully described hereinafter. The said lever 2 is formed with a "turn-back" bevel 17 over which the pins 12 ride, when the wheel 13 is turned counter-clockwise, with the effect of camming the entire upper portion of the lever rearward sufficiently to let the pin ride over it, this idle movement of the lever being permitted by the reduction of its lower end in thickness, as at 18. When, therefore, the disk 13 is turned counter-clockwise in setting the clock, the pins 12 ride idly over the lever without moving it counter-clockwise, leaving it in its normal position of engagement with the stop-pin 10. At its upper end the lever 2 is formed with a beveled finger 19 which co-acts with the beveled tooth 20 of the counter-weighted lifting-dog 9 which

is hung by a headed stud 21 upon the horizontally arranged lifting-lever 22, the said dog being limited in the range of its movement by a stop-pin 23 mounted in the lever 22 and extending into a circular opening 24 in the dog.

During the quarter hours, the quarter-hour-chime pins 12 by pressing against the face 11 of the lever 2, successively push the same from left to right against the tension of its spring 6. During this time the straight edge of the finger 19 engages with the edge of the tooth 20 of the dog 9 and turns the dog on its stud 21 against the counter-weighted end of the dog, whereby the finger 19 passes under the nose 20 of the dog so as to be shifted from the left to the right hand side of the said tooth, the dog now dropping back into its normal position with the beveled edge of its tooth in opposition to the beveled edge of the finger 19. Now at the termination of the quarter hour, the active pin 12 having moved the lever 2 into its blow delivering position passes the point 16 at the lower end of the face 11, permitting the spring to act and snap the lever by a quick movement from right to left during which movement the beveled edge of its finger 19 engages with the beveled edge of the tooth 20, and bodily lifts the dog 9, and with it the lifting lever 22, and in turn the stop-lever 25, the lower edge of which rests upon an integral rounded bearing surface 26 extending upward from near the free end of the lever 22.

The outer end of the said stop-lever 25 mounts a stop-pin 27 projecting rearwardly through a slot 28 in the movement-plate 3 into position to engage with a shock-absorbing finger 29 riveted to the fly 30 of the chime-train which may be of any approved construction and arrangement, and does not, therefore, require detailed illustration or description. So far as shown, it 40 consists of an arbor 31 mounting the fly 30, a pinion 32 forming a part of the said arbor and meshing into a chime-wheel 33 on an arbor 34 furnished with a pinion 35 meshing into another wheel of the chime-train. The 45 lifting of the stop-lever 25 in the manner described, thus instantaneously releases the chime-train, the lifting of this lever having been effected, as described, through the medium of the counter-weighted dog 9, the 50 spring-actuated releasing-lever 2, the lifting-lever 22 and the stop-lever 25, which parts take the place of the warning mechanism ordinarily employed for warning the chime-train.

60 The lifting-lever 22 is formed with a hub 36 by which it is mounted upon the projecting forward end of an arbor 37 journaled in the front movement-plate 3 and in the complementary rear movement-plate 38, and 65 carrying upon its projecting rear end, a

count-wheel latch 39, the finger 40 of which rides upon the count-wheel 41 and its complementary sustaining-disk 42, which form no part of my present invention. The said count-wheel 41 is carried by a hub 43 also 70 carrying a wheel 44 and mounted upon the projecting rear end of an arbor 45, driven by the chime-train. The said wheel 44 meshes into a wheel 46 at the inner end of the chime drum 47, the pins 48 of which engage with lifting fingers 49 depending from hammer-plates 50 pivotally mounted upon a horizontal stud 51 supported at its inner end in the rear movement-plate 38 and at its outer end in a triangular tie-plate 52. The 75 respective hammer-plates 50 are formed with hammer-tails 53 the upper edges of which engage with a flat, fibrous buffer 54 applied to a buffer-plate 55 supported by a bar 56 extending between the movement-plate 38 and the tie-plate 52 which also supports the outer bearing 57 of the drum 46. The hammer-plates 50 carry hammer-wires 58 mounting the hammers 59. The intermediate movement-plate 60 provides for the 80 mounting of the time-train, though this is not shown.

My present invention is not further concerned with the chime, strike and time-trains which I have deemed it unnecessary to illustrate and describe in detail, but which are sufficiently indicated by the chime-train main wheel 60^a and winding arbor 61, the time-train main wheel 62 and winding arbor 63, and the strike-train main wheel 64 and 100 winding arbor 65.

In the operation of my improved clock, the quarter hour pins 12 acting through the releasing lever 2 counter-weighted lifting dog 9, lifting lever 22, and stop-lever 25, 105 release the chime-train every quarter hour through its fly, without warning the chime-train as the term "warning" is understood in this art. The chimes are sounded on the quarter hours, and at the conclusion of the 110 fourth quarter which will be on the hour, the chiming mechanism is caused to release the strike-train by suitable mechanism forming no part of my present invention and not shown or described. The term "self-contained" as used by me in the foregoing description and in the appended claims to characterize my improved clock-movement, is employed in the sense of a clock-movement in which the time, strike and chime-trains 115 are all organized together on and between the same movement-plates, whereby I not only secure compactness of form, but also avoid the objections incident to and inseparable from the common separately organized time and chime mechanisms co-operably related by parts reaching from one to the other. When such independently organized mechanisms are independently mounted in a 120 wooden clock-case the slightest warping of 125

the same will result either in the failure of the two mechanisms to function properly or not at all. Moreover, when the time and chime mechanisms are independently organized,

- 5 the parts connecting them for their coöperation, are necessarily long and springy and are therefore not only unreliable even when perfectly adjusted, but also are liable to become bent or displaced or otherwise deranged.
- 10 I am aware, however, that a self-contained clock - movement in which the chime and strike trains are organized on and between the same movement - plates is not broadly new. I do not therefore claim such a construction broadly, but only my particular self-contained time, strike and chime-movement characterized by the non-warning release of the chime-train.

I claim:—

- 20 1. In a self - contained time, strike and chime clock-movement, the combination with the time and chime mechanism thereof, of a spring-actuated releasing-lever periodically moved by the time-train into its blow-delivering position, and a lifting-dog operated by a blow delivered by the said releasing-lever for releasing the chime-train without "warning" the same.
2. In a self - contained time, strike and chime clock-movement, the combination with the time and chime mechanisms thereof, of a spring-actuated releasing lever periodically moved by the time - train into its blow - delivering position, a lifting-dog operated by a blow delivered by the said lever when the same is released by the time-train, a lifting-lever mounting the said dog, and a stop-lever operated by the said lifting-lever and directly coöoperating with the chime-train
- 35 for releasing the same without "warning."
3. In a self - contained time, strike and chime clock-movement, the combination with the time and chime mechanisms thereof, of a spring-actuated releasing-lever periodically moved by the time-train into its blow-delivering position, a lifting-dog operated by a blow delivered the said lever when the

same is released by the time-train, a lifting-lever mounting the said dog, a stop-lever operated by the said lifting-lever and directly coöoperating with the fly of the chime-train for releasing the said chime-train without "warning" the same.

4. In a self - contained chime clock, the combination with the time and chime trains thereof, of a chime-disk mounting chime-pins, a releasing-lever having an operating-face whereby the lever is operated by the said pins, and with a beveled turn-back face whereby the lever is pushed into a clearance position by the said pins in turning back the clock in setting, the said lever being periodically moved into its blow-delivering position by the time-train, a lifting dog operated by a blow delivered by the said releasing-lever, a lifting-lever mounting the said dog, and a stop-lever operated by the said lifting-lever and co-acting with a member of the chime-train for releasing the same without "warning."

5. In a self - contained chime - clock, the combination with the time and chime-trains thereof, of a releasing - lever periodically moved into its blow-delivering position by the said time - train and formed with a beveled operating-finger, a counter-weighted lifting-dog formed with a beveled tooth for co - acting with the said beveled finger, whereby the dog is idly operated when the lever is moved in one direction and actively operated when the lever springing in the opposite direction, delivers a blow upon it, a lifting-lever mounting the said dog, and a stop-lever lifted by the lifting-lever and directly co-acting with the chime-train for releasing the same without "warning."

In testimony whereof, I have signed this specification in the presence of two subscribing witnesses.

WILSON E. PORTER.
